S. C. PRICE.

OIL CAN.

APPLICATION FILED MAR. 3, 1921.

Patented Apr. 11, 1922.

Inventor.
Stephen C. Price,
by Ripley Kingsland,
his Attorney.

UNITED STATES PATENT OFFICE.

STEPHEN C. PRICE, OF LOUISIANA, MISSOURI, ASSIGNOR TO BARNETT & WILSON INVESTMENT COMPANY, OF ST. LOUIS, MISSOURI, A CORPORATION OF MISSOURI.

OIL CAN.

1,412,090.

Specification of Letters Patent. Patented Apr. 11, 1922.

Application filed March 3, 1921. Serial No. 449,367.

To all whom it may concern:

Be it known that I, STEPHEN C. PRICE, a citizen of the United States, residing at the city of Louisiana, county of Pike, and State 5 of Missouri, have invented a new and useful Oil Can, of which the following is a specification.

This invention relates to oil cans.

An object of the invention is to provide 10 an oil can having a flexible discharge passage, with a device for supporting the flexible passage in position to cause the oil that remains in the passage after use to drain back into the can.

15 Another object of the invention is to equip an oil can of the character mentioned with a device for supporting the flexible discharge passage in position to cause the oil that remains therein after use of the can to drain back into the can, said device being arranged so that it will not extend greatly beyond the sides of the can and will not interfere with the placing of the can in a package or wrapper for shipment or other purposes.

25 Another object of the invention is to equip an oil can of the character mentioned with a device for supporting the flexible discharge passage to cause oil that remains in the passage after use of the can to flow back into 30 the can, said device being arranged so that it will move or may be moved out of the way when it is desired to use the can, and so that it may be adjusted in such position that it will not interfere with the wrapping or pack- 35 ing of the can.

Other objects will appear from the following description in which reference is made to the drawing showing a convenient embodiment of the invention, and in which 40 the view of the drawing is an elevation having the flexible passage engaged with the holding device to permit the oil to drain back into the can, and in which the dotted lines show different positions of the holding 45 device and of the discharge passage.

As shown the can 1 has a handle 2 on one side thereof and a hopper 3 at the upper end and at the side of the can opposite from the handle 2. When the can is tilted or inclined 50 the oil will flow into the hopper 3 and thence to any point of discharge or use through a flexible tube 4. The tube 4 is preferably a flexible metallic tube and is so constructed that it may be bent or curved to any de- 55 sired shape or position to facilitate the dis-

charge of the oil to any point of use. The tube 4 is comparatively stiff so that it will remain in any position or adjustment in which it is placed.

The present invention consists of a device 60 for supporting the tube 4 in position to discharge the oil that remains after use of the can back into the can. In the embodiment shown said device comprises an arm 5 pivoted by means of a bracket 6 to the upper wall of 65 the hopper 3. The arm 5 has a loop 7 on its free end adapted to receive the end of the tube 4 to hold the tube in the position shown, so that the oil remaining in the tube after use will drain back into the can. 70

When the tube 4 is disengaged from the loop 7 and is bent to a different position the arm 5 may follow the tube as indicated by dotted lines, until the arm rests upon the hopper 3. When it is desired to wrap or 75 place the can within a package the arm 5 may be turned to a position in which it rests upon the handle 2 in which it will be seen that said arm does not extend greatly beyond the plane of the handle 2, and, therefore, does not interfere with the wrapping of the can or the placing of the can within a package. The freedom of movement of the arm 5 to position for use, or to positions in which it is out of the way when it is desired 80 to use the can, or to wrap the can or place the can within a package is an important feature of the invention. 85

From the foregoing it will be seen that the present invention satisfactorily accomplishes 90 all of its intended objects. The specific construction and arrangement of the device for holding the tube in position to cause the oil to drain into the can may be varied without departure from the nature of the invention. 95

What I claim and desire to secure by Letters Patent, is:—

1. The combination with a can, and a flexible tube connected with the can above the level of the contents for conducting the contents of the can to a point of use, of a device in connection with the can arranged to engage with the tube to support the tube so that all points along the tube from the influent end to the effluent end are higher than 105 the other points toward the influent end of the tube, to cause all of the contents remaining in the tube after use to flow back into the can.

2. The combination with a can, a hopper 110

in connection with the upper open end of the can above the level of the contents of the can, and a flexible discharge tube for conducting the contents from the hopper to a point of use when the can is tilted or inclined, of a device in connection with the hopper for holding the flexible tube with the open effluent end thereof above the influent end and above the intermediate portions of the tube to cause all the contents remaining in the tube after use thereof to flow back into the can.

3. The combination with a can, and a flexible tube in connection with the can above the level of the contents thereof for conducting the contents of the can to a point of use, of an arm having one end pivotally supported by the can, and a loop on the opposite end of the arm for engaging the tube to support the tube with the effluent end thereof above the remaining portions of the tube to discharge all the contents of the tube back into the can. 15 20

STEPHEN C. PRICE.
